UNITED STATES PATENT OFFICE.

NOBLE E. CROTHERS, OF PAXTON, ILLINOIS.

CHECK-ROW PLANTER.

SPECIFICATION forming part of Letters Patent No. 318,874, dated May 26, 1885.

Application filed January 26, 1885. (No model.)

To all whom it may concern:

Be it known that I, NOBLE E. CROTHERS, a citizen of the United States, residing at Paxton, in the county of Ford and State of Illinois, have invented certain new and useful Improvements in Check-Row Planters, of which the following is a specification, reference being had to the accompanying drawings.

This invention relates to certain improvements in check-row planters, and it has for its object to provide for automatically operating the slides of the planter to drop the corn or other grain at proper intervals, as more fully hereinafter specified. These objects I attain by the means illustrated in the accompanying drawings, in which—

Figure 1 represents a perspective view of a planter, showing my improvement applied thereto. Fig. 2 represents an elevation of one side of one of the hoppers, showing my improved device applied thereto. Fig. 3 represents a detached view showing the lever which drives the slides and its adjusting mechanism. Fig. 4 represents a detached view of one of the set of pulleys and rollers between which the knotted operating cord or rope passes. Fig. 5 represents a detached view of a device which I term a "driver." Fig. 6 represents a detached perspective view of the angle-lever; and Fig. 7 represents a perspective view of a modification of my apparatus.

The letter A indicates the frame of the planter, which is mounted on runners B; and B', the grain-hoppers, one located at each side of the planter, as shown in Fig. 1 of the drawings.

The letter C indicates a metallic bracket having laterally-projecting arms c c' c at each end and in the center. The arms c c are provided with vertical shafts d d', upon which are mounted the rollers D and the pulleys E, between which the knotted cord passes.

The central stud has mounted upon it an intermittently-rotating lever, F, which I term a "driver." The said lever is provided with transversely-located forks G at the ends, between which the knotted cord before mentioned passes.

Near one end of the bracket, between the driver and roller and pulley, is pivoted an angle-lever, H, which is provided with a fork at one end, through which the knotted cord

also passes, the other end being provided with a semicircular stud, H', which alternately engages and disengages the lever F, for the purpose hereinafter explained. The said lever F is provided with a bent arm, f, which has a vertical pin, g, to which may be attached the socketed end of the rod I, which extends to the center of the planter when it is adjustably attached to the upper end of the lever K, which is in turn adjustably secured in a sleeve, L, provided with trunnions, which are journaled in bearings in the uprights M of the frame N, secured to the frame of the planter midway between the two boxes.

The adjustment of the rod before mentioned may be effected in any convenient manner; but in the present instance the mechanism consists of a slotted head, h, which is screwed to the end of the rod and held by a joint-nut, i, as shown in Figs. 1 and 3 of the drawings. The adjustment of the lever is effected by a set-screw, k.

One set of operating devices is arranged at the outside upper edge of each hopper, as shown in Fig. 1, with the knotted cord passing between the parts, as above described and illustrated in Figs. 1 and 2 of the drawings. The cord is stretched from end to end of the field to be planted, and the planter is moved in the direction of the arrow, the rod I being connected to the operating devices at one side, as shown in Fig. 1 of the drawings. The cord slips through the devices, which are held in a locked position, until one of the knots comes in contact with the forked end of the lock-lever H.

This it moves until the semicircular stud is disengaged from the driver, after which the knot engages one of the forks of the driver, and as the planter advances gives it a semi-rotation, causing the lock-lever to again engage the driver and hold it until the next knot comes into operation, when the parts again go through the same movement. When the planter has arrived at the end of the row and it is desired to work back again over the field, the planter is turned and placed in proper position, and the lever is shifted to the opposite side, being connected with the pin of the operating mechanism on that side.

The knotted cord is then arranged to pass between the mechanism on that side, and the planting is

continued. It is evident that this reversing operation may be continued from time to time until the field is planted.

By the adjusting mechanism the height of 5 the slide-lever may be adjusted, as well as its stroke, as may be required.

In the modification shown in Fig. 7 of the drawings, the frames C are constructed to slide 10 on the bars C', which are secured to the supporting-strips C'', attached to the sides of the hopper. The frames C are in this instance provided with set-screws C³, and are adapted to be moved along the bars C', and held in position thereon by means of the set-screws. By 15 this means the frames may be set back or ahead in order to drop the corn at the knot on the wire.

I am aware that a centrally-pivoted rod for actuating the slide-lever, said rod being reversible for use on either side of the planter, 20 has been employed. I am also aware that prior to my invention check-row planters have been provided with intermittent rotary mechanism actuated by the tappet-wires and controlled by latches. I therefore do not claim 25 such mechanism, broadly; but

What I do claim, and desire to secure by Letters Patent, is—

1. The combination, in a check-row planter, 30 of the rollers and pulleys mounted on a bracket

on the sides of the hoppers, the lock-lever forked at one end and provided with a semi-circular stud at the other, the driver mounted on the bracket intermediate of the roller and lock-lever and having transverse forks at each end, and the adjustable slide-operating mechanism connected to the driver, substantially as described.

2. The combination, with the operating devices arranged at opposite sides of the hoppers, of the reversible rod connecting at one end with such devices, as at g, and the other end adjustably connected to lever K, as at i h, 40 said lever K being supported in a frame and adjustable by a set-screw, substantially as described.

3. The combination of the driver having forks G and bent arm f, and the slide-operating lever, the lever K, adjustable by a set-screw and supported in a frame, the rod I, 50 connected at one end to the operating devices, as at g, and connected at its other end to lever K by the adjustable head h and joint-nut i, substantially as described.

In testimony whereof I affix my signature in 55 presence of two witnesses.

NOBLE E. CROTHERS.

Witnesses:

GEORGE ROGERS,
PHINEAS L. STRONG.
